ATTORNEY

UNITED STATES PATENT OFFICE.

JOHN A. JONES, OF MANSFIELD, OHIO.

SASH-LOCK.

1,303,677.

Specification of Letters Patent. Patented May 13, 1919.

Application filed August 25, 1916. Serial No. 116,890.

To all whom it may concern:

Be it known that I, JOHN A. JONES, a citizen of the United States, residing at Mansfield, in the county of Richland and State of Ohio, have invented certain new and useful Improvements in Sash-Locks, of which the following is a specification.

This invention has relation to window sash locks and the nature and objects thereof will be readily apparent to those skilled in the art to which it appertains in the light of the following explanation, of the accompanying drawings, illustrating what I now believe to be the preferred embodiment or mechanical expression, of my invention from among other forms and arrangements, within the spirit thereof or the scope of the appended claim.

However, an object of the invention is to provide a sash lock including correlated members adapted to be secured to each sash for coöperation to lock the sashes against relative movement.

Another object of the invention is to provide a sash lock of the character described adapted to lock the sashes against relative movement subsequent to adjustment in any position relative to each other or to the window frame, and to bind the sashes against the window frame to prevent rattling of the sashes in any adjusted position.

A still further object of the invention is to provide a sash lock of the character set forth, adapted to be disposed adjacent the sides of the sashes, and embodying means for locking the sashes against relative movement, and resiliently compensating for differences in width of sashes and other details of construction, thereby enabling the device to be used on windows of various types.

A still further object of the invention is to provide a sash lock of the character set forth which is adapted to lock the sashes against movement relative to each other in any relatively adjusted position thereof, and to further lock the sashes simultaneously against movement relative to the window casing, in any relative adjusted position of said sashes relative to said window frame.

In addition to the foregoing my invention comprehends improvements in the de-

tails of construction and arrangement of parts to be hereinafter more fully described and particularly set forth in the appended 55 claim.

In the accompanying drawings in which similar and corresponding parts are designated by the same characters of reference throughout the several views in which they 60 appear;

Figure 1, is a fragmentary view in front elevation of window sashes illustrating the application thereto of my improved sash lock.

Fig. 2, is a sectional view partly in elevation taken through the meeting sashes of a window illustrating further the application and relation thereto of the members of my improved sash lock.

Fig. 3, is a horizontal sectional view taken on the line 3—3 of Fig. 1, and

Fig. 4, is a similar view on line 4—4 of Fig. 1.

Fig. 5, is a view in transverse section 75 taken centrally through the device.

In the accompanying drawings, 10 and 11 indicate respectively the lower and upper sashes of a window guided in outer and inner guiding strips 12 and 13 respectively 80 and separated by means of parting strip 14.

The upper sash 11 is provided upon the inner face of one of the vertical side members with a vertically extending rack bar 85 15, having apertured terminals 16 through which suitable threaded fastenings 17 pass to secure said rack bar to the sash.

The locking member of my sash lock, is mounted upon the upper edge of the lower sash and comprises a casing 18 flanked at 90 either side by apertured ears 19 through which suitable threaded fastenings 20 pass to secure the casing to the sash. The casing is substantially semi-circular with the diametrical portion facing the outside of the window. The casing 18 is provided substantially centrally in its top plate with an opening 21. A locking plate 22 is superposed above and exteriorly of the casing and comprises a discous member having an eccentrically disposed square opening 23 through which the squared shank 24 of a bolt passes, the said bolt having a hemispherical head 25. Along the diametrical sides of the casing are

formed two inwardly extending lugs 26 located near the ends of the casing and a shorter lug 27 between them. The curved side of the casing also has a short lug 27 as best seen in Fig. 4, and thus the two lugs 27 project toward each other. Lugs 28 are also formed upon the top plate of the casing and depend therefrom in spaced relation to each other, these lugs standing along a line 10 transverse to a line through the lugs 27, as also seen in Fig. 4. A pair of flat spring members 29 are located interiorly of the casing and disposed at opposite sides of the squared shank 24 of the bolt, and are adapted 15 to engage opposite sides of said shank. The terminals of one spring member are adapted to rest against the lugs 26, the terminals of the opposite spring member resting against shoulders 30, formed within the 20 casing, the terminals of the springs being thus brought adjacent one another to place the springs under tension and press them more firmly against the squared shank of the bolt. A rectangular washer 32 is held 25 between the lugs 28 and engaged against the lugs 27 whereby to hold said washer against rotation. The washer is formed with a transversely elongated opening 31 to receive the lower end of the shank 24 which is reduced and rounded to enter said opening. The reduced end of the bolt subsequent to its insertion in the washer is then upset to prevent separation of the washer and shank. The locking member just described is located 30 upon the top rail of the lower sash in close proximity to the rack bar 15, for co-operation therewith.

The construction of my invention having been described in detail, its operation may 40 be briefly stated as follows: The sashes are moved relatively to each other to provide an opening at the top or bottom of the window as the case may be. Previous to such movement of the sashes however, the locking 45 plate is rotated by means of an integrally formed finger piece 33 so as to retain the plate out of the path of movement of the rack bar 15, or vice versa. Subsequent to adjustment of the sashes in proper relation, 50 the locking plate 22 is rotated by means of its handle so as to dispose its periphery in between two of the teeth of the rack bar 15. In this position of the locking plate, the same being shown in Fig. 3, the opposing 55 faces of the squared shank of the bolt 24 will bear against the spring members 29 and the shank will thus be held resiliently in its shifted position. Obviously when the plate is to be disengaged from the rack bar 15 it 60 is rotated in a converse direction, whereupon the spring members 29 are slightly separated by engagement of the corners of the squared shank of the bolt therewith, and continued rotation of the plate and conse-

quently the squared shank of the bolt brings 65 the opposite faces of said shank again into engagement with the spring members whereupon the locking plate is resiliently held in its newly adjusted position.

Thus it will be seen that the sashes may be 70 held or locked together in any position relative to each other, and within limits of the rack bar 15. It is to be further noted that owing to the provision of the transversely elongated opening in the washer 32, the 75 shank 24 is permitted to have slight transverse shifting movement against the tension of the leaf springs embracing the same permitting the locking plate 22 to move laterally as well as rotatably. Thus in addition 80 to locking the sashes against relative movement the sashes are urged toward lateral separation so as to bind them against the guiding strips 12 and 13, to prevent rattling. Thus, a double locking of the sashes is provided, namely, relative to each other, and 85 relative to the window frame. Owing to this arrangement, the upper sash for instance, may be lowered, and locked to the lower sash, both sashes being simultaneously 90 engaged against the window frame. An opening at the upper portion of the window is thus provided. In a similar manner the lower sash may be moved upward, locked to the upper sash, and both sashes engaged 95 against the frame. On the other hand, the sashes may be moved toward each other so as to provide an opening at the top and bottom of the window and locked to each other 100 engaged against the frame.

While I have illustrated and described my invention with some degree of particularity, I nevertheless realize that in practice various alterations thereover may be made, and I therefore reserve the right and privilege of changing the form of the details of construction, or otherwise altering the arrangement of correlated parts without departing from the spirit of the invention or the scope of the appended claim.

Having thus described my invention what I claim as new and desire to secure by Letters Patent is:—

In a sash lock, the combination with an upright rack bar adapted to be secured to 115 the side rail of one sash; of a hollow casing having one flat side and one curved side and ears at its extremities adapted to be secured upon the top rail of the other sash, its top plate having a transverse opening, 120 lugs projecting inward from its straight side, shoulders at the ends of its curved side, lugs depending from said top plate and from the midlength of both sides, a washer mounted within the space bounded by said 125 lugs and having an elongated opening, a disklike locking plate overlying said top plate and adapted to coact with the rack

bar, a bolt whose upper end is fastened eccentrically through the disk and whose body is loosely mounted in the openings in said top plate and washer and is squared between these openings, a spring resting on said end-most lugs and bearing against one side of said square body, and another spring resting against said shoulders and bearing

against the other side of said body, the whole substantially as described.

In testimony whereof I affix my signature in presence of two witnesses.

JOHN A. JONES.
